United States Patent Office

Des. 213,716

Patented Apr. 1, 1969

213,716

COMBINED CANISTER SET, BASE AND COVER THEREFOR

Jack Solomon, Brooklyn, N.Y., assignor to Lincoln Metal Products Corporation, New York, N.Y., a corporation of New York

Filed July 16, 1968, Ser. No. 12,792

Term of patent 14 years

Int. Cl. D7—01

U.S. Cl. D44—6

FIG. 1.

FIG. 2.

FIG. 4.

FIG. 3.

FIG. 5.

FIG. 6.

FIG. 7.

FIG. 1 is a perspective view of a combined canister set, base and cover therefor showing my new design;

FIG. 2 is a top plan view thereof;

FIG. 3 is an elevational view thereof;

FIG. 4 is a front elevational view of one of the full size canister members;

FIG. 5 is a bottom plan view of the canister member shown in FIG. 4;

FIG. 6 is a side elevational view thereof; and

FIG. 7 is a side elevational view of one of the half size canister members.

I claim:

The ornamental design for a combined canister set, base and cover therefor, substantially as shown.
